UNITED STATES PATENT OFFICE.

ALFRED OWEN CROZIER, OF NEW YORK, N. Y.

ART OF MAKING FACED CEMENTITIOUS PRODUCTS.

1,376,321.

Specification of Letters Patent. Patented Apr. 26, 1921.

Application filed June 14, 1918, Serial No. 239,926. Renewed July 21, 1920. Serial No. 398,044.

To all whom it may concern:

Be it known that I, ALFRED OWEN CROZIER, a citizen of the United States, temporarily residing at New York, in the county and State of New York, have invented certain new and useful Improvements in the Art of Making Faced Cementitious Products, of which the following is a full, clear, and exact description.

10 This invention relates to the manufacture of concrete bricks, blocks, hollow tile, and other cementitious products, provided on one or more surfaces with a facing or layer of different character, as for example different in consistency, composition, or color, etc., and the chief object of the invention is to provide a simple, effective and economical method for the purpose. To this and other ends the invention consists in the novel procedure hereinafter described.

15 Various steps in the preferred mode of practising the invention are illustrated in the accompanying drawings, in which are also shown, somewhat diagrammatically, certain parts of the apparatus which I prefer to employ.

Referring to the drawings:

Figure 1 is a rear view, partly in vertical cross-section, of the upright hollow shaft or container in which is established and maintained a cementitious column of slushy concrete.

20 Fig. 2 is a section about in line 2—2 of Fig. 1, showing also the knives by which the lower portion of the cementitious column is severed and divided, and the removable pallet or closure, with a facing layer thereon, in position at the bottom of the shaft or container.

25 Fig. 3 is a sectional plan view on line 3—3 of Fig. 2.

30 Fig. 4 is a section similar to Fig. 2 but showing a method of introducing a layer of facing material into the shaft or container at one side of the same.

35 Fig. 5 is a horizontal section on a plane corresponding to line 5—5 of Fig. 4, showing the arrangement when a facing layer is to be provided on two contiguous sides of the cementitious product or products.

40 Fig. 6 is an end view of a pallet with a layer of facing material thereon.

45 Fig. 7 is a perspective view of a pallet load of faced brick.

Fig. 8 is a perspective view of a faced block, on the pallet on which it is formed.

Fig. 9 is a perspective view showing a facing layer on a piece of woven fabric to give a corresponding texture to the facing.

Fig. 10 is a perspective view showing a pallet load of brick faced on the upper side.

Fig. 11 is a perspective view showing a fabric on top of a suitably supported block to impart to the surface of the latter a corresponding texture.

Fig. 12 is a perspective view of a brick or block faced on one side and on an adjoining end.

Fig. 13 is a perspective view illustrating a simple and convenient method of forming a facing layer on a pallet.

Fig. 14 is a perspective view illustrating a simple and effective way of applying a facing layer on the upper surface of a block or other product.

Fig. 15 is a side view, partly in section, illustrating a method of imparting a rock-like surface or other finish to the blocks or bricks.

55 In carrying out my invention in the preferred manner I employ an upright hollow shaft or container 15, closed at the bottom by a removable pallet 16 resting on a table 17 which can be raised and lowered by means of any convenient and suitable mechanism, not shown.

60 In the lower part of the shaft, at a suitable distance above the pallet, according to the thickness of the products which are to be made, the front and rear walls of the shaft are provided with horizontal slots 18, 19, to receive a horizontal knife 20, and with vertical slots 21, 22, to receive vertical knives 23. The knives mentioned are by preference rigidly connected together, and are reciprocated at the proper times by suitable means, not shown. The shaft preferably has an upward taper, as indicated, at least above the horizontal slots. Preferably the front and rear walls of the part below the slot are parallel but the side walls are slightly inclined though to a less extent than the side walls above the slots.

65 The shaft 15 is filled to a suitable height, as will be explained hereinafter) with slush concrete, that is, a mixture containing a cementitious ingredient, sand or other suitable material, and water in excess, preferably considerably in excess, of that re-

quired for complete hydration of the cementitious ingredient. The lower portion of the column thus formed is subjected to a marked unwatering and compacting or "densifying" effect by the weight of the mass above, the water, being lighter, gradually finding its way upwardly. The effect is more or less proportional to the height of the column, and in practice the column is maintained preferably at such a height that the unset products carved or shaped from the said lower portion are unwatered and compacted enough to make them self-sustaining without lateral support. Forcing the knives 20 and 23, of substantial thickness, into the column produces a further compacting of the lower portion, as will be readily understood.

The primary function of the horizontal knife 20 is to sever from the column the compacted and unwatered portion below the slots 18, 19, which portion is then divided into bricks or smaller blocks by the vertical knives 23. These operations having been performed the knives are retracted until the vertical knives are entirely withdrawn, but leaving the horizontal knife in the column. The table 17 and pallet 16, with the severed and divided portion of the column, are now lowered, leaving the upper part of the column resting on the knife 20; the pallet is removed with its load of bricks and carried away to a place where the bricks may be left to set and harden, a fresh pallet is placed on the table, and the latter is raised to bring the fresh pallet into position at the bottom of the shaft. The horizontal knife 20 is then withdrawn, preferably as quickly as possible, whereupon the upper part of the column drops bodily upon the pallet, the violent impact thus produced aiding materially in compacting of the lower part of the column; and the shaft being tapered, the sudden descent of the column tends to open cracks or spaces at the sides of the shaft, into which excess water is sucked and is expelled upwardly, thus aiding in the unwatering of the column.

As the operations described are repeated, the column is maintained at the proper height by supplying fresh cementitious material of suitable consistency at the top, either continuously or at such intervals as may be most convenient or desirable under the prevailing conditions.

The concrete in the lower portion of the column, though "unwatered," is nevertheless "wet" concrete; that is, it contains ample water for hydration of the cementitious ingredient, and is therefore to be distinguished from the "dry" concrete used in so-called "dry processes" of making concrete blocks and other articles.

With a given shaft 15, the number and size of the products formed depend upon the

number and spacing of the vertical subdividing knives, the largest blocks being produced when no vertical knives are used, as is the case, for example, in Fig. 4.

Facings can be provided on one or more surfaces of the products in a variety of ways. One convenient method is illustrated in Figs. 2, 6, 7 and 13. For this purpose a shallow frame 24, which may be of sheet metal, is provided, to fit down upon the pallet 16, as shown in Fig. 13. The opening in the frame (which opening is of the same size as the inside of the bottom of the shaft 15) is filled with the facing material, which may be of any suitable consistency, but preferably more or less slushy. The frame is then removed, leaving on the pallet a layer or relatively thin body of facing material 25, Fig. 6, and the pallet is placed in position at the bottom of the shaft, as shown in Fig. 2. Then when the horizontal knife 20 is withdrawn, the upper part of the column, which was supported by the knife, drops bodily upon the facing layer so that the two are integrally joined, any air between the two is driven out, and the facing layer is compacted, or densified, and unwatered, after which the now faced lower portion of the column is severed therefrom and, if desired, divided into smaller blocks, or bricks. Fig. 7 shows a pallet load of faced brick, and Fig. 8 a single faced block produced in this way. The material for the facing layer can be quite wet, being preferably just "thick" enough to keep from spreading until the pallet is placed under the shaft. Then the heavy impact of the column, when the horizontal knife is withdrawn, and the subsequent pressure exerted by the introduction of the knife or knives, thoroughly compact or densify, or stabilize, the layer so that it will sustain the weight of the block or bricks while hardening.

Another scheme is illustrated in Figs. 10 and 14. In this case the facing layer on the pallet is omitted and the vertical knives 23 are not used. When the pallet is removed from the bottom of the shaft a frame 26, Fig. 14, is set down around the block 27, the frame being slightly higher than the block. The facing material 28 is then deposited on the upper face of the block and leveled off to the top of the frame, after which, if desired, the block can be divided into bricks by means of a gang of knives or wires, not shown. The facing material can be applied quite soft, and when it is applied in a thin enough layer the division of the block into bricks can be effected without waiting for the facing material to set or harden. A pallet load of faced bricks produced in this way is shown in Fig. 10.

In the scheme illustrated in Figs. 4 and 5 I provide within the shaft 15 a plate, as 28, parallel to one wall and spaced at the

proper distance therefrom by means of pins 30, and extending well down toward the path of the knife 20. Into the space thus provided between the plate and the adj^a cent wall the facing material 29 is supplied at a rate to keep pace with the severance of blocks or bricks from the bottom of the column. This facing material can be quite soft. Below the plate the column and the 10 layer of facing material join, as indicated in Fig. 4, and are integrally united by the lateral pressure of the former. To avoid all possibility of rupture of the facing layer and consequent spreading of the column 15 through the layer to the shaft wall at the point of rupture, thereby producing an imperfect or defective facing, the plate is preferably forced down or allowed to fall with the column as the latter descends and then 20 drawn up again before or after the knife is re-introduced into the column to sever the next block therefrom. In this way a layer of facing material is carried down the side of the shaft and applied to the side of the 25 column therein, producing a facing on that side of the products which are cut from the bottom of the column. Vertical knives 23 are not shown in Fig. 4, but it is to be understood that they may be used if desired. 30 If facings are desired on other sides also, additional plates are employed in the column, as for example the plate 31, Fig. 5. In this way all four sides of the block can be faced. At the same time the scheme 35 illustrated in Figs. 2 and 13 may be used, to provide a facing on another face of the block, and the remaining surface can be faced by the method illustrated in Fig. 14. In this way as many surfaces as desired can 40 be faced. Fig. 12 shows a block or brick faced on one end and one side.

The facings can be given a surface design or texture in various ways. For example pallet 16 can be covered with a piece of 45 woven fabric 32 and the facing layer 25 formed thereon, as shown in Fig. 9, in the manner already described in connection with Fig. 13. Then when the column in the shaft 50 descends upon the facing layer the pattern of the fabric is impressed upon the facing. The fabric can be left in place until the material has hardened, or the block can be turned over upon another supporting surface and the fabric peeled off at once. An- 55 other way is to apply the facing by the method illustrated in Fig. 14 and then to apply the fabric on top, as indicated at 33 in Fig. 11, pressing the fabric down upon the more or less yielding mass by means of 60 a roller or otherwise. The fabric is then stripped off and the block set aside to harden.

A finish which for many purposes is highly pleasing and desirable can be given 65 to one or more faces of the blocks or other

products by the method illustrated in Fig. 15. For this purpose the block, brick, or other article, resting on the pallet 16 on which it was formed, or turned over upon another pallet or other suitable support, is 70 inclosed in a lateral support, such as a close-fitting open frame or box 34 and over the surface of the block (which may or may not have a facing layer 35) is strewn sand, 75 crushed rock (for example quartz, marble, or granite), small pebbles, or other mineral bodies of suitable size and desired character and color. These are now pressed into the block or brick to embed them therein, by any convenient means, as for example a 80 plunger or presser-plate 36, actuated by any suitable means not shown. In this way surfaces of a great variety of kinds and textures can be obtained, reproducing or closely simulating natural unpolished stone. If a 85 facing layer 35 is also used it may be rich in cement so as to afford secure anchorage for the embedded particles, and may be colored to harmonize or contrast therewith as may be desirable. Another way of accom- 90 plishing the same or a similar result is to mix the pebbles, crushed stone, or other particles, with the material with which the brick, or block, or other product is to be faced. In such case the rock particles ex- 95 posed at the surface of the facing layer are apt to be coated, more or less, with a film of cement, but such film can be easily removed by a quick washing with a fine spray of water, or, if the material has set or har- 100 dened, with weak hydrochloric acid, leaving the exposed faces of particles clean and bright, like the surface of freshly broken stone, pebbles or pallet.

Still another way of giving a finish to the 105 facing layer is to wipe or beat the surface with a brush of suitable stiffness. Wiping, or drawing the brush over the plastic sur- face, gives a graining effect, straight or wavy, and beating or pounding with the 110 brush gives a rough texture resembling sandstone or other desired face-textures or finishes.

If a smooth, polished, or glazed effect is desired a pallet having a polished surface is 115 used, for example a pallet made of, or pro- vided with a layer or plate of, glass, celluloid, polished metal, or other suitable mate- rial, which imparts a corresponding sur- face to the facing layer formed thereon. 120 This is particularly desirable where the fac- ing is composed of white cement and con- tains fine white sand or crushed white mar- ble.

As before stated, the material of the fac- 125 ing layer or layers may be of widely varying character or consistency or both, depending largely upon the purpose for which the bricks, or other products, are to be used. For example, the facing may be of the same 130

composition as the body of the block, but different in color, or it may be richer in cement so as to give a finer grain or smoother or harder surface; or it may contain an ingredient intended to make the layer water-proof or less absorbent. In general I prefer to have the facing material "wet," that is, containing at least enough water, if not more than enough, for complete hydration. In many cases the facing can be relatively thin, for example about an eighth of an inch thick, inasmuch as the layer is firmly joined to the underlying body of concrete and is, in fact, practically integral therewith.

15 It is to be understood that the invention is not limited to the features herein specifically described but can be practised in other ways without departure from its spirit as defined by the following claims.

20 I claim:

1. In the art of making faced cementitious products or articles, the improvement comprising establishing and maintaining a column of slush concrete of a height enabling the weight of the column to compact and unwater the lower portion of the column, applying a facing layer of cementitious material to the lower portion of the column and utilizing the weight of the column to compact said material and unite it with the column, and shaping a self-sustaining, faced, and unset cementitious article from such lower portion.

2. In the art of making faced cementitious products or articles, the improvement comprising establishing and maintaining a column of slush concrete of a height enabling the weight of the column to compact and unwater its lower portion, applying a facing layer of cementitious material to the lower portion of the column, and passing a knife of substantial thickness into the lower portion of the column to sever the lower portion of the column and simultaneously compact the same.

3. In the art of making faced cementitious products or articles, the improvement comprising establishing and maintaining a column of slush concrete of a height enabling the weight of the column to compact and unwater its lower portion, arranging under the column a suitably supported layer of cementitious facing material, allowing the column to descend upon the layer of facing material whereby said layer is compacted and united with the underside of the column, and shaping a faced, self-sustaining, upset cementitious article from said lower portion.

60 4. In the art of making faced cementitious products or articles, the improvement comprising establishing and maintaining a column of slush concrete of a height enabling the weight of the column to compact 65 and unwater its lower portion, arranging

under the column a suitably supported layer of cementitious facing material, allowing the column to fall suddenly upon such layer whereby the same is subjected to the impact of the column and is compacted and unwatered and integrally united with the column, and shaping a faced, self-sustaining, unset cementitious article from said lower portion. 70

5. In the art of making faced cementitious products or articles, the improvement comprising establishing and maintaining a column of slush concrete of a height enabling the weight of the column to compact and unwater its lower portion, applying to the lower portion of the column a facing layer of cementitious material and utilizing the weight of the column to compact and join to its lower portion said facing layer, severing the lower portion of the column, and cutting through the severed portion and the facing material thereon to form a plurality of faced articles. 75 80 85

6. In the art of making faced cementitious products or articles, the improvement comprising establishing and maintaining a column of slush concrete of such height that the weight of the column will compact and unwater its lower portion, applying cementitious facing material to the lower portion of the column and causing the weight of the column itself to compact the facing material and unite the same with the column, severing the now faced lower portion of the column, and cutting up such severed portion into articles each having a facing on at least one surface. 10 90 95 100

7. In the art of making faced cementitious products or articles, the improvement comprising establishing and maintaining a column of slush concrete of a height enabling the weight of the column to compact and unwater its lower portion, applying a facing layer of cementitious material to the lower portion of the column and utilizing the weight of the column to compact such layer and unite it with said lower portion, and passing a horizontal knife and one or more vertical knives into the lower portion of the column to sever the faced lower portion and divide the same into a plurality of faced, unset, self-sustaining articles.

8. In the art of making faced cementitious products or articles, the improvement comprising establishing and maintaining a column of slush concrete of such height that the weight of the column will compact and unwater its lower portion, arranging below the column a pallet carrying on its upper surface a relatively thin body of cementitious facing material of substantially the same area as the bottom of the column, allowing the column to descend suddenly upon said relatively thin body of facing material whereby the same is subjected to the impact 130

of the column and is thereby compacted and united with the column, and carving one or more faced, self-sustaining, unset articles from the compacted and unwatered lower portion of the column.

9. In the art of making faced cementitious products or articles, the improvement comprising establishing and maintaining a column of slush concrete of a height enabling its own weight to compact and unwater its lower portion, applying a facing layer of cementitious material to the lower portion of the column and utilizing the weight of the column to compact said layer and unite the same with the said lower portion, shaping from the faced lower portion of the column a faced unset self-sustaining article, spreading solid particles of the kind described upon the unset facing on said article, and pressing the solid particles into said facing to embed them therein.

10. In the art of making faced cementitious products or articles, the improvement comprising establishing and maintaining a column of slush concrete of a height enabling the weight of the column to compact and unwater its lower portion, applying a facing layer of cementitious material to the lower part of the column and utilizing the weight of the column to compact said layer and unite the same with said lower portion,

shaping a faced unset self-sustaining article from the faced lower portion, and embedding solid particles of the kind described in the unset facing layer on said article. 35

11. In the art of making faced cementitious products or articles, the improvement comprising forming and maintaining an upright body of wet, compacted, unwatered and unset concrete, causing said body to descend upon and unite to itself a facing layer of cementitious material, shaping from the faced lower portion of said body a faced unset self-sustaining article, and embedding particles of the kind described in a surface 45 of said article.

12. In the art of making faced cementitious products or articles, the improvement comprising forming and maintaining an upright body of wet, compacted, unwatered 50 and unset concrete, causing said body to descend upon and unite to itself a facing layer of cementitious material, shaping from the faced lower portion of said body a faced, unset, self-sustaining article, inclosing said 55 article in a lateral support, spreading upon the unset facing a layer of solid particles of the kind described, and exerting pressure upon the layer of solid particles to embed the latter in said facing. 60

In testimony whereof I affix my signature.
ALFRED OWEN CROZIER.
